(57) **CLAIM**

The ornamental design for an ergonomic toilet seat and lid, as shown and described.

DESCRIPTION

FIG. 1 is a top perspective view of the ergonomic toilet seat and lid, showing my new design with the lid in a partially open position;

FIG. 2 is a front elevation view of the present embodiment, showing the lid in a partially open position;

FIG. 3 is a rear elevation view of the present embodiment, showing the lid in a partially open position;

FIG. 4 is a left side elevation view of the present embodiment, showing the lid in a partially open position, with the right side elevation view being a mirror image thereof;

FIG. 5 is a top plan view of the present embodiment, showing the lid in a partially open position;

FIG. 6 is a bottom plan view of the present embodiment; and,

FIG. 7 is a top perspective view of the present embodiment, showing the lid in a closed position.

1 Claim, 4 Drawing Sheets
